UNITED STATES PATENT OFFICE.

FREDERICK W. BALLARD, OF CLEVELAND HEIGHTS, OHIO, ASSIGNOR TO THE SHERWIN-
WILLIAMS COMPANY, OF CLEVELAND, OHIO, A CORPORATION OF OHIO.

PAINT-SPRAYER.

1,007,667.

Specification of Letters Patent.

Patented Nov. 7, 1911.

Application filed December 30, 1909. Serial No. 535,708.

To all whom it may concern:

Be it known that I, FREDERICK W. BALLARD, a citizen of the United States, and a resident of Cleveland Heights, county of Cuyahoga, and State of Ohio, have invented a new and useful Improvement in Paint-Sprayers, of which the following is a specification, the principle of the invention being herein explained and the best mode in which 10 I have contemplated applying that principle, so as to distinguish it from other inventions.

My invention relates to apparatus for applying liquids by means of air pressure, and 15 in particular it has regard to an apparatus known as an "air brush" adapted to apply paint to a surface by means of a stream of air under pressure.

The objects of the invention are the provision of a device of this character in which the flow of paint and air may be closely controlled by means located conveniently to the operator, and a device which will be simple in its construction and which may be economically manufactured.

The annexed drawing and the following description set forth in detail certain mechanism embodying the invention, such disclosed means constituting, however, but one 30 of various mechanical forms in which the principle of the invention may be used.

In said annexed drawing:—Figure 1 is a side elevation of my improved device; Fig. 2 is a vertical section thereof with certain 35 parts shown in side elevation.

The improved "air brush," or sprayer, which the present invention provides, comprises in the first place, a tubular body which may be conveniently constructed by 40 threading into a member A, a member B of substantially the same diameter. Extending through the member A is an annular passage a, and extending through the member B concentrically with the passage a and 45 within such passage a, is a passage b having a common orifice with passage a. The passage b is enlarged at its rear end at b', and threaded into the member B at the rear end thereof, is a nut b² through which extends a 50 threaded opening. A valve stem C is threaded through the nut b² and has at its inner end a conical point c which is adapted to control the opening between the enlarged portion b' of the inner passage and the normal portion b of such passage, thus forming 55

a needle valve which controls the passage from such enlarged portion to the common orifice of the passages. The valve stem C is provided at its outer end at the rear of the body, with an angled portion c' which forms 60 a handle for the valve stem of the needle valve.

A pipe a' is threaded into member A and opens into the passage a; this pipe is designed to be connected with an air or other 65 fluid pressure supply, and the passage of such fluid pressure through the pipe and into the passage a is controlled by suitable cock a² which is provided exteriorly with an arm a³. A similarly disposed pipe b³ is threaded 70 into the member B and is designed to connect the enlarged portion b' of the inner passage with a paint or other liquid supply receptacle, the passage through this pipe being controlled by a suitable cock b⁴ which is 75 operable by arm b⁵. The body proper is provided with a suitable handle or grip D which is attached to the member B of the body proper in any suitable manner, the handle D preferably depending rearwardly 80 from the body portion of the sprayer. A lever d is pivoted to the handle D and a link d² is pivoted at one end to the lever d and at the other end to the arm b⁵ which operates the cock b⁴ controlling the passage from the 85 paint supply receptacle to the inner passage. A spring d' bearing against the lever d serves to normally retain said lever in retracted position, and hence to hold the cock b⁴ in closed position. 90

The mode of operation of the device may be briefly pointed out with this description in view. The operator holds the device by its handle and turns on the air supply by opening the cock in the air supply pipe, the 95 operating arm of which is obviously conveniently located. The paint supply, however, is normally closed by means of the spring which bears against the operating lever. The operator then may open such 100 paint supply by pressure with his thumb upon the operating lever which is pivoted to the handle, and it will be obvious that, because such supply will remain open only so long as the operator exerts pressure upon the operating lever, he has an absolute and instantaneous control over the supply of paint to the sprayer. Furthermore, by means of the needle valve which controls 105 the flow of paint through the inner passage 110

of the sprayer, the operator may make a very close or fine adjustment of the opening through which the paint flows, and the handle by which the needle valve is operated is located in a most convenient position for manual operation by the operator.

Other modes of applying the principle of my invention may be employed instead of the one explained, change being made as 10 regards the mechanism herein disclosed, provided the means stated by any one of the following claims or the equivalent of such stated means be employed.

I therefore particularly point out and distinctly claim as my invention:—

1. A paint sprayer, comprising a body provided with concentric passages having a common orifice, certain of said passages being connected with a fluid-pressure supply 20 and certain of said passages being connected with a liquid supply, valves respectively located in the fluid-pressure and liquid connections, and a handle disposed at an angle to said body and forming a pistol grip, a 25 thumb lever for operating such valve in such liquid connection, said handle being disposed adjacent to such valve in said liquid connection, whereby said sprayer may be operated with one hand.
2. A paint sprayer, comprising a body provided with concentric passages having a common orifice, certain of said passages being connected with a fluid-pressure supply and certain of said passages being connected 30 with a liquid supply, a needle valve in the liquid passage intermediate the liquid supply connection and the orifice, said needle valve having its stem threaded in, and ex- 35

tending outside of, said body, valves respectively located in the fluid-pressure and liquid connections, and a handle disposed at an angle to said body in the same plane as said connections, said handle being also disposed adjacent to such valve in said liquid connection and forming a pistol grip, whereby said sprayer may be operated with one hand.

3. A sprayer comprising a body provided with two concentric passages having a common orifice, the inner passage being enlarged at its rear end, and pipe for connecting the outer passage with a fluid-pressure supply, a valve in such pipe, a second pipe for connecting the enlarged portion of the inner passage with a liquid supply, a second valve in said second pipe, an arm for operating said second valve, a handle for said body disposed rearwardly thereof in the same plane as said two pipes but at an angle thereto and to said body, said handle forming a pistol grip, a lever pivoted to said handle, a link pivoted to said arm and to said lever, a spring normally retaining said second valve in closed position, and a needle valve controlling connection between the enlarged portion and the normal position of the inner passage, said needle valve having its stem threaded in, and extending outside of, said body.

Signed by me this 28th day of December, 70 1909.

FREDERICK W. BALLARD.
